US0D1063066S

(12) **United States Design Patent** (10) **Patent No.:** **US D1,063,066 S**
(45) **Date of Patent:** **** Feb. 18, 2025**

(54) **CUSHION**

(71) Applicant: **DCSTAR INC**, New York, NY (US)

(72) Inventor: **Ligui He**, New York, NY (US)

(73) Assignee: **DCSTAR INC**, New York, NY (US)

(**) Term: **15 Years**

(21) Appl. No.: **29/943,242**

(22) Filed: **May 21, 2024**

Related U.S. Application Data

(63) Continuation of application No. 29/899,103, filed on Aug. 4, 2023, now Pat. No. Des. 1,034,959.

(57) **CLAIM**

The ornamental design for a cushion, as shown and described.

DESCRIPTION

FIG. 1 is a front view of a first embodiment of a cushion showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a front view of a second embodiment of a cushion showing my new design;

FIG. 9 is a rear view thereof;

FIG. 10 is a left side view thereof;

FIG. 11 is a right side view thereof;

FIG. 12 is a top view thereof;

FIG. 13 is a bottom view thereof; and,

FIG. 14 is a perspective view thereof.

(Continued)

The broken lines depict portions of the cushion that form no part of the claimed design.

1 Claim, 14 Drawing Sheets
